UNITED STATES PATENT OFFICE.

EDWARD N. DILLMAN, OF ST. LOUIS, MISSOURI.

CAR-VENTILATOR.

No. 858,268.

Specification of Letters Patent.

Patented June 25, 1907.

Application filed January 3, 1907. Serial No. 350,579.

To all whom it may concern:

Be it known that I, EDWARD N. DILLMAN, a citizen of the United States of America, residing at St. Louis, in the State of Missouri, have invented new and useful Improvements in Car-Ventilators, of which the following is a specification.

This invention relates to car ventilators, designed particularly for use on railway cars for exhausting the foul air therefrom and maintaining the air therein in a wholesome condition, the object of the invention being to provide a simple, reliable and effective device of this character which is readily applicable to existing car structures to take the place of the ordinary deck screen ventilators.

In the accompanying drawing, —Figure 1 is a top plan view of a car ventilator embodying the preferred form of the invention. Fig. 2 is a horizontal section thereof. Fig. 3 is an outer end elevation looking toward the discharge pipe.

Referring to the drawing, 1 designates the casing of the ventilator, which serves the function of a discharge pipe for the foul air and is secured at its inner end to a baseboard or plate 2, which is applied in practice to the side of the deck of the car to take the place of the ordinary screen ventilator, the board being provided with an opening 3 in communication with the casing and interior of the car.

Arranged within the casing is a suction device comprising a tube 4 divided by a partition 5 to form passages 6 and 7. These passages are in respective communication with conductors 8 and 9 extending from the tube outwardly through opposite sides of the casing and projecting in opposite directions, the outer or inlet ends of said conductors being properly flared for the free admission of air thereto. The inner walls of the conductors are provided with ports 10 and 11 communicating with passages 12 and 13 formed between said conductors and the inner end of the discharge pipe by a partition 14, deflectors 15 and 16 being provided within the conductors to shield said ports and guide the flowing currents of air so as to prevent any retardation in the exhaust of currents of foul air passing into the suction tube 6.

The passages 6 and 7 are controlled by an automatic valve or shutter 17 pivotally mounted at the outer end of the partition 5 on a pivot pin 18, said shutter being provided with angularly arranged leaves or plates 19 and 20 to respectively close said

passages. The shutter is so arranged and the leaves so relatively disposed that the shutter in its opposite movements will alternately and reversely open and close the passages. 60

In practice, it will be understood that the conductors 8 and 9 face toward the opposite ends of the car, and, assuming that the conductor 8 is facing the direction of travel of the train, the air entering through the conductor 8 will swing the valve or shutter to the position shown in Fig. 2, so as to open the passage 6 and close the passage 7. The current of air will accordingly discharge through the passage 6 into the outer end of the discharge pipe 1 and thence to the atmosphere, thus creating a suction in the passage 12, whereby the foul air will be caused to pass from the car into said passage 12, thence through the port 10 into the passage 6 and finally out through the pipe 1 with the suction-inducting current of air entering through the conductor or nozzle 8. The action of the valve in this connection in closing the passage 7 will, it is apparent, prevent air from entering or discharging through the conductor 9, and consequently any back suction that would otherwise take place to retard the discharge of foul air through the acting foul air discharge passage. When the car travels in the opposite direction, the pressure of the air rushing through conductor 9 will swing the valve to open the coacting passage 7 and close the passage 6 to secure the same result, 90 and a suction will be created in the passage 13 and foul air drawn thereinto and discharged through the port 11, passage 7 and outer end of the pipe 1, as will be readily understood. 95

The pipe 1 may suitably incline outwardly and downwardly to allow rain water to freely discharge without entering the ventilator, and the device may be applied to the car in any other suitable manner. 100

It will be seen that the construction of the ventilator is such as to secure a forcible and rapid discharge of the foul air from the car, whereby the air within the car will be maintained in a wholesome condition. 105

Having thus described the invention, what is claimed as new is:—

1. A ventilator of the character described having a pair of air conductors and suction passages communicating therewith and adapted for communication with a car, and a valve or shutter automatically operated 110

when either conductor is in action to close the other conductor.

2. A ventilator of the character described comprising a casing having suction passages, 5 conductors extending therein and communicating at one end with the suction passages and at their opposite ends with the outer end of the casing, and a pivoted valve operative when either conductor is in action to automatically open said conductor and close the other conductor.

3. A ventilator of the character described comprising a discharge pipe or casing provided at its inner end with suction passages, 15 conductors extending into said chamber and having passages communicating at one end with the suction chambers and at the opposite end with the outer end of the discharge pipe, and a pivoted shutter adapted to close 20 the outer ends of the conductor passages, said shutter being automatically operative to open the passage of the active and close the passage of the inactive conductor.

4. A ventilator of the character described 25 provided with a pair of suction and a single outlet passage, conductors communicating with the said passages, and an automatic valve controlling communication between the conductors and outlet passage.

5. A ventilator of the character described 30 comprising a discharge pipe provided at its inner end with suction chambers and having its outer end forming a discharge passage, air conductors entering said pipe and provided with passages opening at their outer 35 ends into said discharge passage and provided at their inner ends with ports communicating with said suction chambers and having deflectors guarding said ports, and a valve for automatically controlling communication 40 between said conductor passages and the discharge passage.

6. A ventilator of the character described comprising a discharge pipe or casing having suction chambers, air conductors communicating with said suction chambers, and a valve 45 controlling communication between the conductors and outlet end of the discharge pipe, said valve being provided with angularly arranged portions operative to open one conductor and close the other conductor, substantially as described.

In testimony whereof, I affix my signature in presence of two witnesses.

EDWARD N. DILLMAN.
